UNITED STATES PATENT OFFICE.

MARSHAL L. COCHRAN, OF GRAND RAPIDS, MICHIGAN.

BENCH-STOOL.

1,385,903.

Specification of Letters Patent. Patented July 26, 1921.

Application filed March 28, 1918. Serial No. 224,849.

To all whom it may concern:

Be it known that I, MARSHAL L. COCHRAN, a citizen of the United States of America, residing at Grand Rapids, in the county 5 of Kent and State of Michigan, have invented new and useful Improvements in Bench-Stools, of which the following is a specification.

The invention relates particularly to stools 10 to be used in conjunction with work benches, and seeks to provide as its principal object, a stool of this character having an adjustable back, so that the back may be shifted to various positions to provide for a restful 15 attitude for the user of the stool.

Another object is to provide a stool of this character having a locker below the seat.

Still another object is to provide a stool 20 made entirely of metal, in order that it may offer great resistance to wear.

Still another object is to provide a stool which is simple in construction, durable and effective in use and inexpensive to manufacture. 25

Still further and other objects will be made to appear in the detail description which follows.

To the exact construction in which the 30 invention is shown it is not to be confined. Certain desirable changes or alteration may be made manifest in the continued practical use of the invention and the right is reserved to make any which do not deviate from the 35 scope of the subjoined claims.

In the accompanying drawings:

Figure 1 is a perspective view of the improved stool.

Fig. 2 is a longitudinal sectional view.

Referring to the drawings, the stool is 40 shown as being provided with four legs 1 which are made preferably of angle iron. The legs are interconnected near their bottom ends by braces 2 which are also made 45 preferably of angle iron, the braces being riveted or otherwise suitably attached to the legs. The seat of the stool comprises a plate 3 on the edge of which the flanges 4 are 50 formed. The seat is designed to sit on top of the legs and the flanges 4 are riveted or otherwise suitably attached to the flanges of the angle irons of which the legs are made.

A locker is formed below the seat 3, the sides of the locker comprising plates 5 whose 55 upper edges abut the bottom of the seat and

whose ends are riveted or otherwise attached to the legs. The back of the locker comprises a plate 6 which is attached in the same way as the plates 5. The bottom of the locker comprises a plate 7 on three edges of 60 which flanges 8 are formed, these flanges being provided for riveted or suitable means for attachment to the plates 5 and 6 at the bottom edges thereof. The front of the locker is closed by a door 9 which is hing- 65 edly connected to the bottom 7, the bottom having no flange on the edge where the door connects with it. A lock 10 is provided near the upper edge of the door for locking the same in a closed position, the free edge of 70 the door being just below the seat 3 and the door being adapted to swing downwardly when moving from the closed to the opened position.

The back of the stool comprises an inverted U-shaped frame made of material which is rectangular in cross section, the legs 11 of the frame being pivotally connected at their free ends to the back legs of the stool not far above the bottom 7 of 80 the locker. The U-shaped frame is adapted to hold the back plate 12 of the stool which comprises a metal plate on whose two side edges flanges 13 are formed, these flanges being riveted or otherwise suitably attached 85 to the legs 11 of the U-shaped frame.

To each of the legs 11 and at a point in the vicinity of the seat 3, there is pivotally connected one end of a bar 14 which is rectangular in cross section, this bar near 90 one end and opening at its lower edge being provided with a series of arcuate slots 15 formed with the pivot connection of the bar as a center. The slots 15 are uniformly spaced one from the other and by means of 95 them the bar is adapted to engage the headed stud 16 which is fixed in one of the flanges 4 of the seat 3. The flanges 4 on both sides of the seat are provided with studs 16 and the bars 14 connected with the 100 legs 11 of the back are adapted to engage the studs, thus holding the back in various angular positions with respect to the seat, depending on which of the slots 15 the studs 16 engage.

It will be observed that by means of the bar 14 the back of the stool may be shifted forward or backward, thus providing for the adjusting of the back suitable to the position which the workman assumes when 110

- working at various machine tools or at the bench, the operation of adjusting the back consisting simply in raising the free ends of the bars 14 to effect their disengagement with certain of the slots 16, whereupon the desired position of the back can be found, after which the lowering of the bars 14 permits the studs to reengage new slots and secure the back in the desired adjusted position. 10
- The arrangement of the angle irons 2 near the bottom of the legs provides for strengthening the legs of the stool and also provides a suitable foot rest for the workman. 15
- The arrangement of a locker provides a convenient compartment in which the workman may keep such tools as he may not care to have disturbed.
- The foregoing description taken in conjunction with the accompanying drawings 20

makes further explanation of the invention unnecessary.

The invention having been described what is claimed as new and useful is:

A device of the kind set forth comprising legs made from angle iron, angle iron braces interconnecting the legs near their bottom ends, a plate having depending flanges on its four edges, the plate resting on top of the legs and the flanges being attached thereto, plates positioned just below the aforesaid plate and connected between certain pairs of legs, a still further plate having upturned flanges by means of which it is connected to the latter plates, and a door plate hingedly connected to the last named plate and provided with means for locking engagement with one of the depending flanges of the first named plate. 25 30 35 40

In testimony whereof I affix my signature.

MARSHAL L. COCHRAN.
